UNITED STATES PATENT OFFICE.

MICHAEL KILLEEN, OF BRADDOCK, PENNSYLVANIA.

TWYER-COOLER.

SPECIFICATION forming part of Letters Patent No. 613,042, dated October 25, 1898.

Application filed October 14, 1897. Serial No. 655,177. (No model.)

To all whom it may concern:

Be it known that I, MICHAEL KILLEEN, of Braddock, in the county of Allegheny and State of Pennsylvania, have invented a new 5 and useful Improvement in Twyer-Coolers, of which the following is a full, clear, and exact description, reference being had to the accompanying drawings, forming part of this specification, in which—

10 Figure 1 shows in vertical section a twyer-cooler, twyer, and a blast-pipe of a blast-furnace, the twyer-cooler being provided with my improved protecting-shield. Fig. 2 is an 15 elevation of the twyer-cooler and shield, and Fig. 3 is a vertical section on the line III III of Fig. 2.

Twyer-coolers for blast-furnaces are tapering annular castings the walls of which are made hollow for the circulation of water and 20 which are adapted to be set in the walls of the blast-furnace, so as to form sockets or holders for the tuyers and to protect the walls around the same.

In the drawings, A represents a twyer-cooler; B, the twyer, which fits in the nose or small end thereof and projects into the furnace, and C is the blast-pipe, which fits into the butt of the twyer and connects the same with blast-main D.

30 As the nose of the twyer B projects a considerable distance into the furnace it frequently happens when the material in the furnace slips after sticking to the side wall that molten iron and cinder will flow back 35 through the twyer into the blast-pipe. As this is a plain pipe and is not water-cooled the contact of such molten material will rapidly burn a hole through it, and the molten stuff escaping through such a hole will strike

40 the side of the cooler and burn it, allowing the water to leak out. This not only causes the loss of the cooler, which is very considerable in itself, but it may require the operation of the furnace to be stopped for several

hours to replace it. It frequently happens, 45 however, that the blast cannot be taken from the furnace as soon as the cooler is burned, because there may be cinder at the openings of the other tuyers, which would flow into them if the blast-pressure were removed; but 50 the longer the blast is kept on the more damage is done by the break at the first twyer and it becomes harder to remove. In order to avoid these very serious difficulties, which 55 have been encountered in blast-furnace practice heretofore, I have devised a protector or shield E, which I place in the large cooler against its inner surface, so that it will reach to the butt of the twyer. When such a shield is present and when any breakout occurs, the 60 molten iron or cinder runs down the shield and is shed by it away from the furnace without harming the cooler. I make this shield of any refractory material, such as asbestos, 65 shaped to fit the inner surface of the cooler, or I may make it of fire-brick in one piece or in sections. I may form studs or ribs F on such shields, so that it can be grouted after 70 being put in place, or I may make the shield out of iron, which is more resisting than copper. I may also cast studs on the inner surface of the cooler and plaster the inside with a coating of fire-clay, using the studs to retain it; but I prefer to use a shield previously 75 formed to the required shape, since such shield can be readily placed in the cooler and is more convenient.

I claim—

In a water-cooled twyer cooler or breast, the combination therewith of a removable protecting-shield of refractory material placed around its inner surface.

In testimony whereof I have hereunto set my hand.

MICHAEL KILLEEN.
